EXTENSIBLE ROLLER SKATE

Marshall H. Frisbie, Branford, Conn., and Howard G. Healey, Hollis, N.H., assignors to The A. C. Gilbert Company, New Haven, Conn., a corporation of Maryland

Filed Oct. 6, 1964, Ser. No. 401,946
3 Claims. (Cl. 280—11.26)

This invention relates to skates and particularly roller skates that are adjustable to fit various foot sizes of the wearer such as growing children under the age of seven. 10

The applicants have found that the lighter weight and less severe service demanded of roller skates in these smaller sizes enable them to be made mainly of impact resistive, molded plastic material if constructed according to the principles and details of the present improvements.

One object of the invention is to avoid the objectionable click-clack noise that is characteristic of roller skates as commonly constructed heretofore of sheet metal parts. 20

Another object is to lighten the weight and improve both the ruggedness and the appearance of roller skates particularly in the sizes used by small children.

Another object is to avoid the surface deterioration to which metallic skates are subject when left exposed to the weather by children.

Another object is to enable the length of the skate to be adjusted easily without the use of tools.

These and other objects of the invention will appear in fuller particulars from the following description of the construction and use of a roller skate embodying the invention in which description reference is had to the accompanying drawing wherein:

FIG. 1 is a top plan view of a sectional roller skate illustrating in reduced size one successful embodiment of the present improvement with the sections adjusted to produce a minimum length of the skate. 35

FIG. 2 is a side elevation of the same skate.

FIG. 3 is an enlarged fragmentary view in section on the plane 3—3 in FIG. 1 looking in the direction of the arrows. 40

FIG. 4 is a view taken in section on the plane 4—4 in FIG. 1 looking in the direction of the arrows.

FIG. 5 is a fragmentary bottom plan view of the skate drawn on the same enlarged scale as in FIGS. 3 and 4 with its parts shifted to extend the length of the skate. 45

FIG. 6 is a fragmentary exploded perspective view of the length determining latch parts of the skate positioned to accord with FIG. 5.

The skate is made in separate platform sections preferably molded from plastic material that is suitably resistant to shocks of impact, said sections comprising a toe upporting section 12 and a heel supporting section 13, the former equipped with the straps 14 and the latter forming a heel guard equipped with instep straps 15 fastening the skate to the shoe heel of the wearer. Sections 12 and 13 are slidable relatively to each other lengthwise of the skate toward and away from a meeting line designated M in FIG. 2, at which line they abut edge-wise when relatively positioned to contract the skate to its minimal length.

Rigidly attached to the toe section 12 by a rivet or other such fastening 16 there is an elongate apertured strike plate 17 which extends lengthwise of the skate across the aforesaid meeting line M in close underlapping relation to both the toe section 12 and heel section 13. Strike plate 17 is held against and in slidable relation to heel section 13 by a retaining stud 18 which mounts a latch member having the form of a leaf spring 19 which serves to retain the strike plate 17 slidably against the

2

bottom surface of heel section 13 with sufficient freedom to permit the leaf spring to slide in unison with the platform section 13 relatively to strike plate 17.

By means of relatively lateral branches 22 of a relatively wide, lengthwise extending aperture 23 cut out of plate 17, strike shoulders 24 are provided in the plate spaced apart lengthwise thereof. The leaf spring 19 has a turned-up catch end 25 capable of detentive engagement with any of the strike shoulders 24. This catch end is normally biased upward by the resilient in the leaf spring and seeks to extend through some one of the aperture branches 22 so as to catch on to the strike shoulder 24 formed thereby.

Leaf spring 19 carries a manually operable actuator in the form of a finger button 28 that is movable upward and downward in an opening 29 in the platform section 13. Thus button 28 is accessible to be reached and depressed by the tip of a person's finger. This shifts the catch end 25 of spring 19 downward and out of engagement with any strike shoulder 24 on which it may be latched. The opening 29 occurs at the meeting line M—M in FIG. 1. Hence it is a split opening which becomes enlarged progressively as toe section 12 and heel section 13 are adjustively separated to lengthen the skate as shown in FIG. 6.

It may be pointed out that strike plate 17 may be a thin sheet metal part stiffened by channel forming edges 32 and that the catch end 25 of leaf spring 19 is permitted to project upward slightly beyond the top surface of strike plate 17 into a slot 33 in the toe section 12. The molded plastic bodies comprising the toe and heel platform sections of the skate are suitably lightened by their ribbed construction without sacrifice of rigidity. The ribbed construction at 34 in each platform section 30 slidably fits and serves as a lateral guide to keep the strike plate 17 aligned with the lengthwise axis of the skate.

FIG. 5 illustrates the mounting of the traction wheels 35 on the toe and heel sections of the skate. An axle bolt 36 is lodged fixedly in a boss 37 on the under face of each section of the skate and with the aid of nut 38 clamps fixedly against each lateral end of boss 37 a headed bearing bushing 39 which may be of any suitable material. The wheels 35 may be molded from suitably durable wear resistant material and have hubs that are freely rotatable on the bearing bushings 39.

At least one of the traction wheels may be equipped with a sound producing vibratory diaphragm 44 from which will emanate a whining or siren imitative sound as the wheel turns. Diaphragm 44 is tightly seated at its peripheral edge in a rabbet-like recess or counterbore in the outside rim of the wheel in which recess is also lodged one end of a cantilever flexible arm 45 whose other end is secured to the center of diaphragm 44 by a rivet or other suitable fastening 46. Midway its length arm 45 dips into contact with the furrowed or ribbed surface of the flange of stationary nut 38 and is constantly biased into yieldable contact therewith either by resilience in the diaphragm 44 or in the arm 45 or both. 50 The diaphragm and arm are removably retained in the hollow of the wheel by a cupped wheel cap 47 that snaps into the aforesaid recess in the rim of the wheel.

The following claims are directed to and intended to cover equivalents of the herein proposed parts and arrangements of parts which fall within a broad interpretation of the nomenclature employed in the claims to define the invention.

What is claimed is:

1. In a roller skate the combination of, toe and heel platform sections relatively slidable toward and away from a meeting line at which said sections abut edge-

wise, an elongate strike plate having a lengthwise extending cutout attached to one of said platform sections at one side of said meeting line and projecting from said one section across said line into underlapping relation to the other of said platform sections, strike shoulders on said plate spaced apart lengthwise thereof, a leaf spring carrying a catch positioned thereon to extend into detentive engagement selectively with said strike shoulders, a manually operable actuator operatively related to said leaf spring in a manner to shift said catch into and out of detentive engagement with said strike shoulders, and a stud extending through said cutout fastening one end of said leaf spring fixedly to said other platform section.

2. In a roller skate the combination defined in claim 1, in which the said cutout has laterally extending branches whose edges comprise the said strike shoulders respectively.

3. In a roller skate the combination of, toe and heel platform sections relatively slideable toward and away from a meeting line at which said sections abut edge-wise, an elongate strike plate attached to one of said platform sections at one side of said meeting line and projecting from said one section across said line into

underlapping relation to the other of said platform sections, strike shoulders on said plate spaced apart lengthwise thereof, a leaf spring anchored to said other platform section on the opposite side of said meeting line carrying a catch positioned thereon to extend into detentive engagement selectively with said strike shoulders, and a finger button upstanding from said leaf spring disposed to be manually depressible for flexing said spring downward to release said catch from detentive engagement with said strike shoulders.
